Inventor

Elijah Eaton

United States Patent Office.

ELIJAH EATON, OF HARTFORD, CONNECTICUT.

Letters Patent No. 89,567, dated May 4, 1869.

TOY-VELOCIPED.

The Schedule referred to in these Letters Patent and making part of the same.

To all whom it may concern:

Be it known that I, ELIJAH EATON, of the city and county of Hartford, and State of Connecticut, have invented certain new and useful Improvements in Toy-Velocipedes; and to enable others skilled in the art to make and use the same, I will proceed to describe its construction and operation, referring to the drawings, in which the same letters indicate like parts in each of the figures.

The nature of this invention consists of a two-wheel velocipede, having an image representing a person seated astride thereof, his feet upon the cranks propelling the machine, his hands upon the steering-helm apparently guiding the course of machine. While the machine is steadied in an erect position and guided by a tedder-bar, in a given circuit, one end of this bar is secured to the velocipede. The other end is secured to the upper end of an operating-shaft, which is impelled or actuated by weights, spring, or clock-work, &c.

In the accompanying drawings—

Figure 1 is an isometrical view of this invention.

a is a table.

b is a box, upon which the table is secured, in which any common mechanism adapted for propelling or actuating motion to a shaft, is arranged as a clock-movement, weight, spring, &c., as in common use.

c is a perpendicular shaft arranged in bearings inside of the box *b*, and to which the propelling-power is attached, in any of the common ways of applying power to a shaft.

There are various ways and various kinds of mechanism for producing motion to shafts. I do not, therefore, wish to claim or be confined to any particular motive-device.

d is a tedder-bar, one end of which is secured to the upper end of the shaft *c*, and the other end to the frame-work *e* of the velocipede.

f are the wheels.

g is the seat.

h is the rider.

Now, by winding up the machine, or the mechanism which actuates the driving-shaft of the machine, by the key *i*, and removing the key from its socket, the velocipede, with its rider, will travel in a given circuit upon the table *a*, thus presenting the appearance of a person actually propelling the machine in a circuitous route, greatly to the amusement of children, and but little less so to persons of more mature age.

I believe I have thus shown the nature, construction, and operation of this invention, so as to enable others skilled in the art to make and use the same therefrom.

What I claim, and desire to secure by Letters Patent, is—

A toy-velocipede, constructed and operating substantially as shown and described.

ELIJAH EATON. [L. s.]
